UNITED STATES PATENT OFFICE

2,295,941

SINGLE TRIGGER DEVICE

Frederick T. Fahlen, Phoenix, Ariz.

Application March 31, 1939, Serial No. 265,352

11 Claims. (Cl. 42—42)

This invention relates to improvements in small firearms, more especially to the trigger mechanism of said firearms. According to the instant disclosure the improved trigger mechanism is embodied in a double-barreled shot gun, either of the horizontal or over and under types (or rifles), but this disclosure is not to be regarded as a limitation upon the adaptation of the invention because its principles are such as to make it suit other ordnance of the same general kind.

Reference is made to Patent 2,134,604, of October 25, 1938; to Frederick T. Fahlen for a single trigger device, of which the instant invention is a particular improvement. The instant disclosure represents a simplification of the patented device at least in respect to the trigger arrangement. The firearm is now equipped with a solitary trigger as distinguished from the twin triggers of the patent, said solitary trigger being made to perform all of the functions capable of being performed by the twin triggers, and in addition to that said solitary trigger has instrumentalities for enabling the selection of the barrel to be fired first.

This provision for selection is a development from the fact that the respective barrels of either of the foregoing types of double-barreled shot guns are of full caliber and choke caliber bores. Usually the right barrel has the full caliber bore while the left barrel has the choke bore. The full caliber bore provides for shooting an object at a less distance from the gun than that for which the choke bore is intended. The latter prevents a spreading of the pellets of the shell when the latter is fired, the resulting reduced dispersion enabling long-range shooting more effectively than with the full caliber bore. With this preamble in mind the objects of the invention are as follows:

First, to provide a trigger mechanism for a plurally-barreled firearm, which mechanism is so constructed as to make it possible for the shooter to choose the barrel to be fired first, that barrel thus becoming the leader of the firing sequence, the main functions necessary to the accomplishment of said sequences being under the direct control of a solitary trigger.

Second, to provide a trigger mechanism for a double-barreled shotgun or rifle (but which as far as the principle of said mechanism is concerned might comprise more than two barrels), employing a solitary trigger having an auxiliary sear embodied in it to constitute a unitary combination therewith, said auxiliary sear being sub-

ject to a step setting whereby to determine which of the two barrels is to be fired first.

Third, to provide a trigger mechanism of the immediately preceding kind, wherein the step setting of the auxiliary sear is accomplished by the safety device, whether for the normal resetting of the auxiliary sear for an established firing sequence, or for an abnormal setting of the auxiliary sear to change the firing sequence.

10 Fourth, to provide for an arc of idle motion of the solitary trigger during an involuntary pull thereof following the firing of a barrel, said arc occurring between the auxiliary sear and the right angled finger or other equivalent part of at least one of the principal sears.

15 Fifth, to provide a firearm of the foregoing character wherein the spring-pressure progression of the trigger-carried auxiliary sear is controlled by the coaction of a latch, also trigger-carried, with the trigger plate, the displacement of the latch and the release of the auxiliary sear being accomplished automatically upon pulling the trigger.

20 Sixth, to provide a firearm wherein the principal sear is employed as a detent for the trigger-carried auxiliary sear, the riding of the latter against the principal sear providing the previously mentioned arc of idle motion.

25 Seventh, to provide a firearm wherein the solitary trigger has combined with it the means for changing the adjustment of the auxiliary sear, both said sear and the latch for the latter being mounted on the trigger.

30 Other objects and advantages will appear in the following specification, reference being had to the accompanying drawings, in which:

35 Figure 1 is a side elevation of a Winchester gun receiver, illustrating the embodiment of the improved trigger mechanism, the auxiliary sear being in the position of its manual or abnormal setting.

Figure 26 is a view similar to Fig. 25 illustrating the action of the mechanism upon the first release of the trigger.

Figure 27 is a perspective view of the lever structure by which the auxiliary sear in Fig. 23 is adapted to be set.

Figure 28 is a perspective view of one side of the modified auxiliary sear.

Figure 29 is a perspective view of the opposite side of said auxiliary sear.

In carrying out the invention the improved trigger mechanism is shown embodied in a receiver designated 1 in Fig. 1 and 1a in Fig. 17. The reason for the distinction is that Fig. 1 down to Fig. 16 illustrates the adaptation of the invention to a Winchester gun while Fig. 17 down to Fig. 22 illustrates the adaptation of the invention to a Parker gun. All parts in the lat-

ter agreeing with those in the Winchester receiver are identified by corresponding reference numerals without necessarily repeating the description, supplemented with the exponent letter *a* to keep the distinction clear.

The receiver 1 is to be regarded as belonging to a double-barreled shot gun. The barrels are omitted. One of the hammers is shown, namely the left hammer 3. The right hammer is not shown but it will be understood that the right principal sear 4 (Figs. 3 and 4) is the same in every respect to the left principal sear 5, the functions of these sears, as is commonly known, being to hold the respective hammers in their cocked positions, as in the instance of the hammer 3 (Fig. 1). Each of the hammers is spring-pressure operated. For this purpose each has a notch 6, as in the instance of the hammer 3, to which one end of a heavy spring (not shown) is applied, the opposite end of said spring being anchored in the forward end of the receiver.

Each hammer also has a bottom shoulder 9, as in the instance of the hammer 3 (Fig. 1) with which the respective principal sear 5 engages to hold the hammer in its cocked position. The trigger is now designated 6. This is a solitary trigger. It is pivoted at 10 to a mount 11 which is generally made integral with the trigger plate 12.

Attention is directed to the structure of the solitary trigger 6. This has a plate portion 13 (Fig. 12) which is continued as spaced upward extensions 14, 15. These extensions define a recess 16 for the occupancy of the auxiliary sear. The plate portion 13 has a bore 17 which begins at the bottom 18 of the recess and is driven well toward the trigger 6 as clearly shown for example in Fig. 10.

Slots 19 provide openings between the bore 17 and the sides of the plate portion 13. This bore is for the occupancy of the latch. A slender rod 20 is fixed at its extremities in the extensions 14, 15 in spaced relationship to the bottom 18 and in parallelism thereto, and in a position to intersect the axis of the bore. In other words, the rod 20 occupies a position directly over the open end of the bore.

The extension 14 has a hole 21 for the reception of the pivot pin 10. The extension 15 has an offset 22 in the direction of the extension 14, so as to overlie a part of the recess 16. This offset broadens the bearing for a lug on the safety setting rod. The top of the extension 15 is grooved at 23.

The previously mentioned auxiliary sear is generally designated 24 (Figs. 13 and 14). It comprises a relatively small block of metal which is generally defined by a midportion 25. The top edge of this midportion has three staggered teeth 26, 27, and 28. The first tooth 26 comprises an extension of the front sear wall 29. The bottom part of this same wall comprises the front of a bottom tooth 30. The latter has a companion tooth 31. Thus there are three teeth on top of the midportion 25 and two teeth on the bottom thereof.

Said teeth except 31 have the profile of saw teeth, the bevels situated medially thereof being useful in accomplishing a more easy sliding of the auxiliary sear under the right angled extensions of the principal sears 4, 5. The teeth 26, 30, are extended laterally at 32 to one side of the midportion 25. The teeth 27, 31 are extended laterally at 33 (Fig. 14) to the other side of the midportion 25. The tooth 28 is part

of an enlargement 34 which also extends laterally of the midportion 25 and to the same side as does the extension 32. Said lateral extensions are continuous from top to bottom, defining flutes contiguous to the extensions which constitute unobstructed passageways. These passageways, because of their lack of any obstructions from top to bottom, are a positive assurance against an inadvertent raising of the undesired sear, it being said passageways that are momentarily occupied by the inwardly directed fingers of the sears in the act of firing as later explained. A bore 35 runs longitudinally of the midportion 25 and provides for the slidable mounting of the auxiliary sear upon the rod 20.

A spring 36 tends to keep the auxiliary sear 24 pressed forwardly of the trigger 26 in the recess 16. This spring is carried by a portion of the rod 20, its opposite ends abutting the extension 15 and the inner side of the auxiliary sear. To this end the lateral extension of the enlargement 34 is useful in increasing the area of the contiguous spring abutment.

By virtue of the fact that the rod 20 passes directly over the latch bore 17 it follows that the auxiliary sear 24 will be guided correctly with respect to said bore. The nether side 37 of the auxiliary sear is flat and rests upon the bottom 18. The bottom edges of the teeth 30 and 28 also ride the bottom, this arrangement preventing the turning of the auxiliary sear on the rod 20. A latch 38 (Fig. 15) is slidably carried in the bore 17. This latch has a single tooth 39 which is adapted to engage either one of the teeth 30, 31 (Figs. 2 and 6).

The purpose of this latch is to hold the auxiliary sear 24 back against the tension of the spring 36. Its primary purpose is to retain the auxiliary sear in either one of two positions for initially raising either the left or the right principal sear upon the first pull of the trigger 6. When in the first position (Fig. 2) the tooth 26 is adapted to raise the left sear 5 on the first pull of the trigger 6. When in the position in Fig. 6, the tooth 27 is adapted to raise the right sear 4 upon the first pull of the trigger 6.

A spring 40 in the bore 17 beneath the latch 38 presses the latter upward. The latch usually has a hole 41 (Fig. 15) for the occupancy of the upper end of said spring, although this is not always essential. A pair of laterally directed pins 42 ride the slots 19 and extend slight distances beyond the side faces of the plate portion 13 so as to be engageable with the nether face of the trigger plate 12.

It is this engagement which causes the automatic recession of the latch 38 into the bore 17 upon the pulling of the trigger 6 (Figs. 4 and 8). The latch is thus released from the auxiliary sear and the latter is enabled to make a forward step under the impulse of the spring 36.

The setting yoke (Fig. 16) now designated 43, comprises a fork 44 which depends from a block 45. This block has a hole 46 which receives the rod 47 (Fig. 1) of the conveniently termed setting device 48. A pin 49 is driven through the block and the rod, each having matching holes for the purpose to secure the yoke 43 on the setting rod.

Said setting device, incidentally comprising known structure in the Winchester gun, comprises a finger-piece 50 which is slidable on the upper receiver plate 51. This finger-piece has depending lugs 52, 53, which ride in a slot 54 in

the upper plate. The neck 55 of the safety lever 56 rides between these lugs and as the finger-piece 50 is slid back and forth the safety lever is turned on its pivot 57. The latter has a mount on the trigger plate 12.

The setting rod 47 is pivoted at 58 to the safety lever 56. Said rod has cross sectionally round and rectangular parts, as can readily be deduced from Fig. 1, the cross sectionally rectangular part having a depending lug 59 which is adapted to override the trigger offset 22 and hold the trigger down against being pulled. This comprises the safety position, and it is so designated and shown in full lines in Fig. 1. The round part of the setting rod is slidably guided in a hole in the mount 11, the front end of said rod being so positioned with respect to certain gun parts 60 that when motion is imparted to the latter in the cocking of the gun by means of the lever 61, a backward thrust is imparted to the setting rod so as to shift it from an inwardly forward position (arrived at by sliding the finger-piece 50 to the safety-off position) to the full line position previously mentioned.

A leaf spring 62 is mounted on the lugs 52, 53, the former having a cross pin 63 which sustains the bowed spring in its frictional working position against the nether side of the upper plate 51. The front end of the leaf spring is bent into detent form at 64, and this detent is adapted to snap into either of two recesses 65, 66, agreeing with the safety position and the safety-off position of the safety lever 56. A trigger spring 67 is mounted on the safety lever 56. One of its free ends bears up against the rod 47, the other free end being pocketed in the groove 23 of the trigger 26.

Attention is again directed to the right and left sears 4, 5 (Fig. 4). These have the customary inwardly directed fingers 68, 69 (Fig. 3). These fingers or their equivalents which are common in the Winchester and Parker guns, are herein made to serve a new purpose, namely, to coact with the auxiliary sear 24 (Fig. 13) to produce what is conveniently termed an arc of idle motion. This arc of idle motion represents an involuntary relaxation of the trigger 6 and an immediately succeeding involuntary after pull following the discharge of the first barrel. It is this involuntary pulling of the trigger which in some known types of guns causes the premature and unwanted discharge of the second barrel. The unwanted motions mentioned above cannot be prevented, but they can be dissipated so as to be rendered harmless, and this is accomplished by providing for the foregoing arc of idle motion.

These statements afford the opportunity for describing the operation of the form of the invention in Figs. 1 to 16. The finger-piece 50 (Fig. 1) is ordinarily adapted to be manually slid forward one step. The cocking lever 61 is turned to recock the hammers after the barrels of the gun have been fired. The cocking is accompanied by a motion of the gun parts 60 which thrusts the setting rod back to the full line or safety position (Fig. 1). The lug 59 is then positioned over the offset 22 and the trigger 6 cannot be pulled. It is now that the slide 50 is moved one step forward. This will be the safety-off position. It is not indicated in the drawing, but it is easily understood that the lug 59 will stand in advance of the offset 22 and that in accordance with this the setting rod 47 will be in the forward position from which it eventually

will again be thrust back upon a repeated cocking of the hammers.

The order of firing is herein regarded as a normal right-left raising of the hammer sears to fire the concomitant barrels. That is to say, in the case of the horizontal barrel type the right barrel is adapted to be fired first, and then the left barrel. In the superimposed type either the top or bottom barrel can be fired first. In order to bring this about the setting yoke 43 will push the auxiliary sear 24 back only far enough to let the latch 38 engage the companion tooth 31. From this it will be understood, as has been suggested already, that the sole function of the setting yoke 43 is to reset the auxiliary sear 24 after the firing has been done.

The extent of backward movement of the yoke 43 in the normal resetting of the device 48 to the safety position is only enough to push the auxiliary sear 24 into position for the engagement of the latch 38 with the tooth 31. That position of the auxiliary sear is shown in Fig. 6. The sear tooth 27 is then in registration with the finger 68 of the right sear 4 (Fig. 7). The tooth 28 is still behind the finger 69 of the left sear 5.

Now visualize a pulling of the trigger 6 from the position in Fig. 6. This can be regarded as the first pull, counting from the particular position of the auxiliary sear 24 now under discussion. The first pull designated in Fig. 4 is based upon a reverse firing sequence which is presently described.

The first pull now under discussion is shown in Fig. 8. The tooth 27 raises the right sear (arrow a). The right barrel will be fired. The lateral pins 42 engage the nether side of the trigger plate 12 which produces a depression of the latch 38 (arrow b). This releases the auxiliary sear 24 from the latch. The auxiliary sear moves forward a slight distance, eliminating the space c (Fig. 7), the lateral enlargement 34 of the tooth 28 then abutting the finger 69 of the left sear 5 (Fig. 9).

It is now that the arc of idle motion is readily visualized. The left sear 5 is still down. Its position will match that of the right sear in Fig. 4. The enlargement 34 has virtually the entire vertical thickness of the finger 69 to rub against during the involuntary vibration of the trigger 6, following the firing of the right barrel, the finger 69 thus acting as a temporary stop against the immediate further forward advance of the auxiliary sear. The trigger can be vibrated with the utmost freedom, either involuntarily or voluntarily, but as long as the enlargement 34 stays and rubs against the finger 69 the auxiliary sear will be stopped from its next forward step and it will be impossible to fire the left barrel.

Inasmuch as the enlargement 34, as in the instance of the other tooth enlargements, is clear from top to bottom there is no obstruction that could engage the finger and thus inadvertently lift the left sear against the intentions of the user.

The firing of the left barrel is accomplished upon a full relaxation of the trigger 6. That position is shown in Fig. 10. The auxiliary sear 24 now moves to its farthest front position. The setting yoke 43 acts as a stop. The auxiliary sear overlies the latch 38 and keeps the latter depressed. The lateral enlargement 34 of the tooth 28 is now in registration with the finger 69 of the left sear 5 (Fig. 11). The next pull of the trigger 6 will, obviously, raise the left sear and fire

the left barrel because of the tooth enlargement 34 being under said finger.

Thus the firing order of the gun will be right-left, this being predicated on an automatic resetting of the auxiliary sear 24 by the shifting of the setting device 48 to the full line safety position by the normal cocking of the hammers. The result is that the full bore barrel is discharged first and then the choke bore barrel. This order can be reversed for a left-right firing which will discharge the choke bore first and then the full bore. This reversal involves a manual back setting of the finger-piece 50. This is an abnormal setting so termed for convenience to emphasize the fact that the reversal of the right-left firing order occurs only occasionally. The finger-piece 50 is slid back to the dotted line position (Fig. 1). The detent 64 leaves the recess 65 whereupon it is simply permitted to rub against the nether side of the plate 51.

The sole function of this abnormal setting of the finger-piece 50 is to bring the setting yoke 43 back to the dotted line position d (Fig. 1). In doing so the auxiliary sear 24 is pushed back one step farther than it is in the previously described normal operation. In other words, the latch 38 is made to catch the bottom tooth 30. This is shown in Fig. 2 and it is from there that the trigger pulling sequences in Figs. 2 to 10, specifically designated in Figs. 4 and 8, are readable.

The tooth 26 is in registration with the finger 69 of the left sear 5 (Fig. 3). This means that the left sear is the first of the sears to be raised (arrow e, Fig. 4) upon the first pull of the trigger. The latch 38 is again depressed (arrow f) by the engagement of the lateral pins 42 with the nether side of the trigger plate 12. The arc of idle motion comes in evidence again. The auxiliary sear then slips forwardly, eliminating the space g (Fig. 3), and bringing the lateral extension 33 of the tooth 27 against the right sear finger 4. It is unnecessary to repeat the functions incidental to this engagement, it being thought sufficient to say that the auxiliary sear is held back by the finger 68 until there is a full relaxation of finger pressure upon the trigger. The latter then assumes the position in Fig. 6. The latch 38 engages the auxiliary sear in the companion tooth 31. The enlargement of the tooth 27 is now in registration with the finger 68 of the right sear 4. That sear is raised (arrow a, Fig. 8) by the second pull of the trigger. When the trigger is again released (Fig. 10) the auxiliary sear 24 makes another step forward, but this time the step is idle and of no consequence because even if the trigger were pulled again the resulting raising of the left sear would not result in any response from the left barrel because of its having previously been fired.

Reference is now made to Figs. 17 to 22 wherein the trigger 6a and auxiliary sear 24a are modified slightly to suit the characteristic action of the Parker setting device 48a. In this gun the trigger plate 12a carries a bracket 79 which elevates the pivot 57a of the safety lever 56a to a position approximately half way between the plates 12a and 51a. A rearward push on the loosely coupled setting rod 47a, in the cocking of the hammers by means of the cocking lever 61a, turns the safety lever 56a in the clockwise direction, as in the instance of Fig. 1, but due to the elevation of the pivot 57a the extension 71 of said lever proceeds forwardly and this is contrary to the action of the safety lever 56 in Fig. 1.

The result of this is that the auxiliary sear 24a is driven forwardly for resetting instead of rearwardly as in Fig. 1.

This reversal of function requires the following slight changes in the trigger and in the auxiliary sear. The offset 22a is now decidedly forked at 12 (Fig. 20). This fork is the result of deepening the groove 23 (Fig. 12). The fork 12 virtually constitutes a groove, but in any event it provides a guide for the terminal 13 of the auxiliary sear (Fig. 21), the purpose of said terminal being to provide for the abutment of the extension 11 so that the auxiliary sear is moved forward readily when the safety lever 56a is turned in the proper direction.

A cylinder rod 14 extends forwardly from the auxiliary sear. This rod is loosely fitted in a bore 15 in the mount 11a. The latter provides the abutment for one end of a spring 16. The other end abuts the auxiliary sear and its purpose is to tend to move the auxiliary sear backward.

The setting device 48a involves a slightly different structure from the setting device 48 in Fig. 1, but the principle of operation is the same. The nether side of the upper plate 15a is now shown with an extra recess 11 as a supplement to the safety and safety-off recesses 65 and 66a. The detent 64a on the finger-piece-carried member 62a is adapted to occupy any one of the various recesses.

The operation of the trigger mechanism for the Parker gun is now briefly described. Upon swinging the lever 61a for cocking the hammers the setting rod 47a moves backwardly and shifts the safety lever 56a to the full line position (Fig. 17) from the dotted line position. The setting device 48a is then in the safety position. This act causes the extension 11 to move the auxiliary sear 24a to the position shown in Fig. 17.

The latch 38a holds the auxiliary sear at the companion tooth 31a. The tooth 21a is in position to actuate the right sear 4a first. The finger-piece 50a is slid forwardly to the safety-off position, thus to restore the safety lever 56a to the dotted line position and to permit the raising of the trigger when finger pressure is applied.

This act will cause the firing of the right barrel. The arc of idle motion then occurs between the finger 69a of the left trigger and the enlargement 34a of the tooth 28 precisely as before (Figs. 8 and 9).

Upon releasing the trigger the auxiliary sear moves back until the rear surface of the tooth 26a abuts the adjacent wall of the extension 15a. The tooth 28a is then in registration with the left sear finger 69a, and a subsequent pulling of the trigger then causes the firing of the left barrel. It will be understood from this that the automatic setting of the auxiliary sear 24a by means of the setting rod 47a, as when cocking the hammers by turning the cocking lever 61a, initiates the right-left firing order as in Fig. 1.

The reversal of this order is obtained by sliding the finger-piece 50a back one step from the safety-on position. This is done manually. The result is a clockwise swinging of the safety lever 56a from the full line position in Fig. 17 and an arrival of the parts at the position shown in Fig. 18. The extension 11 again acts as a pusher against the terminal 13, but this time the auxiliary sear 24a is moved one step farther front so that the latch tooth 39a catches it at the bottom tooth 30a (Fig. 18). The finger-piece 50a is next slid all the way front (dotted lines Fig. 17), leaving the trigger 6a free to be pulled.

It is readily understood from Fig. 18 that the tooth 26a will actuate the left sear 5a first, being in registration with the finger 69a. The latch 38a is released by engagement with the bottom of the trigger plate 12a as in Fig. 4, and the auxiliary sear is next caught by the latch in its companion tooth 31a. The second pull of the trigger actuates the right sear 4a because of the tooth 21a being in registration with the finger 68a. Thus the firing order in the abnormal adjustment of the setting device is left-right.

Figs. 23 to 29 illustrate a further modification wherein the auxiliary sear is adapted to be manually set with respect to the trigger which carries it. In this modification all parts agreeing with Fig. 1 are given corresponding numbers without necessarily repeating the description, these being supplemented by the exponent letter b.

It is desired that the Winchester receiver of Fig. 1 be visualized in connection with this modification. The setting rod 47b has a setting yoke 43b as before, this yoke being adapted to automatically shift the auxiliary sear 24b which in this instance is accomplished by a turning.

The trigger 6b has an extension 15b surmounted by the offset 22b which in this instance is deeply forked at 18. Again this fork is a virtual equivalent of the groove 23 (Fig. 12). The space is now used for the mounting of the pivot pin 19 of the latch 38b. The latter is now of the swinging type. It has a heel 80 on one end and a head 81 on the other end. The heel 80 is adapted to engage the setting rod, a spring 82 tending to hold it in the engaging position.

The auxiliary sear 24b (Figs. 28 and 29) has an arrangement of teeth 26b, 27b and 28b matching the tooth arrangement in Fig. 13. These teeth have lateral enlargements 32b, 33b and 34b which appear as extensions beyond the opposite sides of the mid portion 25b. This portion is now extended so that it comprises a pivot plate 83. Said plate has a non-circular hole 84 which receives the correspondingly shaped key portion 85 (Fig. 27) of a shaft 86 of the lever structure 87 in Fig. 27.

A lever 88 on one end of the shaft (Figs. 23 and 27) provides for the manual turning of the auxiliary sear. The other end of the shaft is threaded at 89 (Fig. 27) to receive the securing nut 90. The lever structure 87 may be held in place by other suitable means, but the arrangement shown in Fig. 27 makes it clear that the auxiliary sear 24b is intended to be held rigidly on the shaft 86 so that the auxiliary sear will turn when the lever 88 is moved in the proper direction.

The pivot plate 83 of the auxiliary sear is mounted on the shaft 86 and has a pocket 91 (Fig. 25) in the trigger. Said pocket has an opening 92 to one side which contains one end of a spring 93. The other end of said spring occupies an opening 94 in the auxiliary sear. The function of the spring is to tend to turn the auxiliary sear counter-clockwise, but this turning is prevented as long as the head 81 of the latch is in engagement with one of the auxiliary sear teeth.

Fig. 23 illustrates the position of the trigger mechanism immediately following the resetting of the setting device 48b by means of the setting rod (47 in Fig. 1). The resulting safety position is shown in full lines. The safety-off position is arrived at by sliding the finger-piece (50 in Fig. 1) forwardly one step. The auxiliary sear 24b

is left in the full line position (Fig. 23). The relationship of the teeth 27b, 26b to the right and left sears makes it easy to visualize the right-left firing of the barrels by succeeding pulls of the trigger 6b.

The first pull is illustrated in Fig. 25. The counter-clockwise motion of the trigger (arrow h) causes a clockwise turning of the latch 38b (arrow i) because of the pressure of the heel 89 against the setting rod 47b. The same motion of the trigger is imparted to the auxiliary sear (arrow j Fig. 25). The right sear 4b is lifted (arrow k), causing the firing of the right barrel.

However, the left sear 5b remains in the down position and the now released auxiliary sear 24b may swing forwardly only far enough to bring the tooth 28b in engagement with the finger 69b of the left sear. It is this engagement which again provides for the arc of idle motion emphasized before.

The voluntary release of the trigger brings the parts to the position shown in Fig. 26. The tooth 28b is now in registration with the finger 69b, and the second pull of the trigger will cause the firing of the left barrel. Fig. 24 illustrates what has been called the abnormal adjustment of the auxiliary sear. Instead of using the finger-piece (50 in Fig. 1) for that purpose, the lever 88 is pushed in the clockwise direction from the dotted to the full line position, causing the latch head 81 to engage the tooth 27b. This adjustment holds the tooth 26b in registration with the finger 69b of the left sear 5b. The first pull of the trigger then actuates the left sear to cause the firing of the left barrel first. The order of firing is then left-right, a reversal of the normally adopted arrangement.

I claim:

1. In a double-barreled firearm having hammers for the respective barrels, sears to hold the hammers cocked and a solitary trigger for causing the release of the hammers, movable means turnably carried by the trigger in a normal starting position, being sequentially engageable with the hammer sears to successively actuate said sears upon consecutive pulls upon the trigger, cocking means for the hammers, including a setting device normally but automatically operative by the act of cocking to restore said movable means to said starting position, and a manually operable finger piece carried by the trigger and adapted for manual turning to set the movable means ahead of its starting position for a change in its sequence of engagement with the hammer sears.

2. In a double-barreled firearm having hammers for the respective barrels, sears to hold the hammers cocked and a solitary trigger for causing the release of the hammers, a toothed auxiliary sear turnably carried by the trigger being engageable first with one hammer sear and then with the other hammer sear to successively release the hammers upon consecutive pulls upon the trigger, cocking means for the hammers, including a setting device adapted for rectilinear movement to shift said auxiliary sear as to its initial relationship to the hammer sears, and a latch pivoted on the trigger, having a head engaging a sear tooth to hold the sear, said latch having a heel engageable with a part of the setting device for automatic displacement of the latch upon a trigger pull to release the auxiliary sear.

3. In the receiver of a double-barreled firearm having hammers for the respective barrels,

sears to hold the hammers cocked and a solitary trigger for causing the release of the hammers, movable means carried by the trigger, being sequentially engageable with the hammer sears to successively actuate said sears upon consecutive pulls upon the trigger, latch means to hold said movable means in a normal starting position, and means abutted with the receiver upon a pull of the trigger to displace the latch means and initiate the departure of the movable means from said starting position for the completion of its sequence.

4. In the receiver of a double-barreled firearm having hammers for the respective barrels, sears to hold the hammers cocked and a solitary trigger for causing the release of the hammers, movable means carried by the trigger and adapted to assume progressively stepped positions to engage the respective hammer sears in sequence upon consecutive pulls upon the trigger, latch means carried by the trigger being engageable with said movable means to hold the latter in each of its stepped positions, and means abutting the receiver upon each voluntary trigger pull, causing displacement of the latch means to release the movable means preparatory to its stepping to the next position.

5. In a lock mechanism for a double-barreled firearm having hammers and sears therefor, said sears having confronting fingers, a solitary trigger pivoted contiguously to said sears, an auxiliary sear movably carried by the trigger, said auxiliary sear having a series of staggered teeth plane-surfaced the full height of the auxiliary sear and alternately in line with the respective fingers, a spring constantly tending to move the auxiliary sear toward the hammer sears to register alternate teeth with the sear fingers thereby to sequentially actuate the hammer sears upon successive pulls on the trigger, said full-height teeth insuring against actuation of a sear by an involuntary after pull of the trigger, and a latch carried by the trigger successively engaging and holding the auxiliary sear between trigger pulls.

6. In a lock mechanism for a double-barreled firearm having hammers and sears therefor, said sears having confronting fingers, a solitary trigger pivoted contiguously to said sears, said trigger having a recess with a bore, an auxiliary sear movably mounted in the recess, said auxiliary sear having a series of staggered teeth alternately in line with the respective fingers and also having other teeth, a spring pushing between the auxiliary sear and a part of the trigger constantly tending to move the auxiliary sear toward the hammer sears to register alternate teeth with the sear fingers, thereby to sequentially actuate the hammer sears upon successive pulls on the trigger, and a spring latch mounted in the bore successively engaging said other teeth of the auxiliary sear to hold it against said spring tension during a voluntary relaxation of finger pressure against the trigger between pulls.

7. In a lock mechanism for a double-barreled firearm having a trigger plate and hammers, said firearm having hammer sears with confronting fingers, a solitary trigger pivoted contiguously to said plate and hammer sears, said trigger having a recess with a bottom having a bore, an auxiliary sear movably carried by the trigger in said recess to ride upon the bottom, said auxiliary sear having a series of staggered teeth alternately in line with the respective fingers and also having other teeth, a spring constantly tending to move the auxiliary sear toward the ham-

mer sears to register alternate teeth with the sear fingers, thereby to sequentially actuate the hammer sears upon successive pulls upon the trigger, a spring latch operable in the bore successively engaging said other teeth of the auxiliary sear to hold it against said spring tension during a voluntary relaxation of finger pressure against the trigger between pulls, and means carried by the latch being engageable with the trigger plate upon a voluntary pull of the trigger to automatically depress the latch and release the auxiliary sear preparatory to an advance thereof by its respective spring and upon the relaxation of finger pressure upon the trigger.

8. In a trigger mechanism, a trigger having a recess provided with a bottom and a bore in the bottom, a rod fixedly carried by the trigger in spaced relationship to the bottom and across the bore, an auxiliary sear slidable on the rod, a spring abutting one end of the auxiliary sear and a portion of the trigger, and a spring latch in the bore releasably engageable with the auxiliary sear.

9. In a trigger mechanism, a trigger having spaced upward extensions defining a recess, said recess having a bottom with a bore, the side walls of the trigger being slotted in communication with the bore, a rod fixed in the extensions in parallelism to the bottom, being spaced therefrom and overlying the bore, an auxiliary sear slidable on the rod, a spring abutting one end of the auxiliary sear and one of the extensions, a spring latch operable in the bore projecting therefrom to obstruct the auxiliary sear, and pins projecting laterally from the latch through the slots for engagement to displace the latch and release the auxiliary sear.

10. In a trigger mechanism, a trigger having spaced upward extensions defining a recess, said recess having a bottom with a pocket, an auxiliary sear situated in the recess comprising a midportion having a toothed upper edge, said teeth having lateral enlargements extending to alternately opposite sides of the mid portion, a pivot plate constituting a continuation of said mid portion and being turnably situated in said pocket, turnable means pivotally supporting said plate on the trigger, a spring tending to turn the auxiliary sear in one direction, and a spring latch movably mounted on one of the extensions, having a head to engage the teeth and a heel adapted for depression to move the latch.

11. In the receiver of a double-barreled firearm having hammers for the respective barrels, sears to hold the hammers cocked and a solitary trigger for causing the release of the hammers, movable means carried by the trigger to actuate the hammer sears upon consecutive voluntary pulls upon the trigger, and successive contact places embodied in said movable means, sequentially riding upon portions of the respective sears, said contact places having uninterrupted plane surfaces from top to bottom of the movable means to assure an unobstructed arc of idle motion of said movable means against the respective sear during an involuntary after-pull of the trigger, thereby to prevent an inadvertent actuation of said sear and to effect a temporary holding of the movable means back from an advance to the next hammer sear.
